UNITED STATES PATENT OFFICE

ANDRÉ HUET, OF PARIS, FRANCE, ASSIGNOR TO THE SUPERHEATER COMPANY, OF NEW YORK, N. Y.

BAFFLE ARRANGEMENT

Application filed September 20, 1930, Serial No. 483,232, and in France May 5, 1930.

The prior art shows baffling arrangements applicable to tubular heat interchangers and particularly to boilers or superheaters in which the baffles are made up on the boiler or 5 superheater tubes themselves which are placed in such relation over one part of their length as to direct the gases along the desired path. One way of making such baffling arrangements is that in which the tubes lying in one plane are bent back on themselves 10 in that plane so as to fill up the spaces between them and thus to form a closed baffle.

The present invention has for its object a baffling arrangement of this sort whose essential characteristic is that the corresponding 15 branches of the several serpentine coils composing the tubular bundle which are normally disposed in different planes so that gas passages are left between them are at those 20 places where baffles are to be provided carried into the same plane in such a manner as to be in contact with each other over a distance extending from one of the walls of the heating or superheating chamber to a point 25 situated at a predetermined distance from the opposite wall.

The description which follows and which makes reference to the accompanying drawing and which is given by way of example 30 will make clear the principle of the invention and the manner in which it can be carried out.

Fig. 1 is a longitudinal section on the line 1—1 of Fig. 2 of a separately fired superheater with my invention applied;

Fig. 2 is a section of the same superheater on the line 2—2 of Fig. 1;

Fig. 3 shows a detail of it on a larger scale, Fig. 4 being a section on line 4—4 of Fig. 3;

Fig. 5 represents likewise on an enlarged scale a further detail of which Fig. 6 is a section on line 6—6 of Fig. 5.

These figures relate always by way of illustration to a separately fired recuperative superheater in which the hot gases coming from source 1 are directed by the tubes 2 and the passage 3 toward the superheating chamber 4, and after having traversed the latter are taken by the fan 5 which forces them in part 50 toward the stack 6 while the other part is

directed by the passages 7 and 8 back to chamber 3 where mixture with the new hot gases occurs.

To provide a baffle in the horizontal plane 9, for example, the corresponding branches of 55 the several serpentine coils lying in said plane are bent into this plane so that they lie side by side over a part of their length and close off for this part of their length the entire width of the chamber.

To complete the baffle on the side toward the wall of the superheater chamber, the elbows 12 forming the ends of the branches 9 are enclosed, for example, with a slight clearance between two horizontal angles 13 fixed 60 to the wall 14 of the superheating chamber and wide enough to make sure that the end of the baffle is closed. Beyond the return bends 12, the tubes are then bent and alternately offset at different heights in such a way as to 65 again form two planes with spaces between the tubes for the passage of gases.

The baffle 17 is formed in a way slightly different from the baffle 9 and shows a variation of the manner in which the invention can 70 be carried out.

In the case of the baffle 17 the adjacent branches instead of terminating in elbows or return bends at the end toward the wall of the chamber are at that end simply bent on 75 80 alternately different radii and are therefore adjacent only at the point 18 where the bending starts. Between this point 18 and the wall 19 of the chamber, tightness is assured for example by a tile 20 lying on the tubes 17 and 85 fixed to the wall by a bracket 21.

The different straight lengths of the tubes constituting the superheater bundle are, according to a known arrangement, of different lengths, the shortest of the lengths being 90 exposed to the highest temperatures. In this way the different lengths expand by amounts approximately equal and the tubes constituting the baffles are thus not subject to warping 95 which would impair the tightness of the baffle.

While I have described the invention as applied to a case where the several straight lengths of the elements are horizontally disposed, and the baffles are therefore also hori- 100

zontal, it will be obvious that this is illustrative only and that the invention is equally applicable to cases where the straight lengths are at some other angle, for example vertical, the gas flow being generally horizontal, the baffles also being vertical. Such variations are to be considered to be within the scope of the appended claims.

What I claim is:

- 10 1. A group of U-tubes arranged close together in parallel planes and having alternately greater and less widths and each having one of its legs in a given plane at a considerable angle to said parallel planes and each having its other leg on the same side of said given plane, said legs in the given plane arranged to form a baffle and the other legs arranged to permit the passage of gases therebetween.
- 15 2. A group of elements, each comprising a plurality of parallel, straight tube-lengths all in one plane, said elements being arranged side by side immediately adjacent to each other, the lengths of alternate elements being relatively staggered to permit gases to pass in a direction generally transverse to the lengths and lengthwise of the elements except where it is desired to form a baffle at which points a tube length of each element is in alinement with a tube length of every other element.
- 20 3. A group of tubular elements arranged to abstract heat from gases flowing therethrough, each having a number of U-loops therein, the legs of said loops being spaced apart throughout portions of the group to permit flow of gases therebetween, and the group having a baffle formed therein by a single leg from each of the elements.
- 25 4. In a heat exchanger the combination of a plurality of elements each comprising a plurality of straight tube lengths and return portions connecting them into a continuous unit for series flow, the lengths of each element lying in a plane and the elements being arranged in adjacent vertical planes, one horizontal plane containing a straight length of each element, these lengths being in contact with each other and forming a baffle, the remaining straight lengths being arranged so any given horizontal plane contains straight lengths of only a part of the elements thereby permitting gas flow across these straight lengths.
- 30 5. In a heat exchanger the combination of a plurality of elements each comprising a plurality of straight tube lengths and return portions connecting them into a continuous unit for series flow, the lengths of each element lying in a plane and the elements being arranged in adjacent vertical planes, one horizontal plane containing a straight length of each element, these lengths being in contact with each other and forming a baffle, the several return portions connecting the last-

named straight lengths to the next succeeding straight lengths being of such forms that these latter lengths do not lie in a common plane, thereby permitting gas flow between them.

6. In a heat exchanger the combination of a plurality of elements each comprising a plurality of straight tube lengths and return portions connecting them into a continuous unit for series flow, the lengths of each element lying in a plane and the elements being arranged in adjacent vertical planes, a plurality of horizontal planes each containing a straight length of each element in contact with each other to form baffles, the remaining straight lengths being arranged so no horizontal plane contains a straight length of each element.

7. In a heat exchanger the combination of a plurality of elements each comprising a plurality of straight tube lengths and return portions connecting them into a continuous unit for series flow, the lengths of each element lying in a plane and the elements being arranged in adjacent vertical planes, a plurality of horizontal planes each containing a straight length of each element in contact with each other whereby baffles are formed, the remaining straight lengths being relatively staggered thereby permitting gas flow between them.

8. The combination in accordance with claim 7 and further comprising a housing enclosing the elements, the plurality of baffles being spaced alternately from opposite ends of the housing.
